UNITED STATES PATENT OFFICE.

EFFINGHAM LAURENCE POLLARD, OF DOBBS FERRY, NEW YORK.

ELECTRICALLY-HEATED SAD-IRON.

1,027,895.

Specification of Letters Patent. Patented May 28, 1912.

Application filed November 22, 1910. Serial No. 593,700.

To all whom it may concern:

Be it known that I, EFFINGHAM LAURENCE POLLARD, a citizen of the United States, resident of the town of Dobbs Ferry, county of Westchester, and State of New York, have invented certain new and useful Improvements in Electrically-Heated Sad-Irons, of which the following is a specification.

10 In experimenting and producing my iron, I have had simplicity uppermost in my mind. Not only simplicity in the first manufacture but particularly as it has to do with the making of the necessary 15 pairs or replacing destroyed or inoperative elements. It has in the past seemed necessary to entirely inclose the resistance material of which the heating element was composed, presumably because of the fear 20 of rupture due to the great expansion from the high heat, and it has in the past been considered necessary to either mold the heating element into the iron or else secure it by such a means as did not allow for easy 25 removal, or exchange or repair.

I have constructed my iron in such a manner as to expose to view the current carrying portion of the heating element, and I have divided the heating element into a 30 number of independent units which though connected together in series are easily removable one at a time from the body or the iron, and I have arranged my iron in such a way that the mere substitution of one 35 heating unit for another will have no effect upon the iron, in fact it is not necessary to allow the iron to become cool before the substitution is made. It will be readily understood that a change from one heating unit 40 to another need not cause the iron to be long out of service, and that even a change sufficient to allow the iron to be used upon another voltage than the one for which it was originally intended requires no great skill 45 and but slight delay.

The following is what I consider the best means of carrying out this invention.

The accompanying drawings form a part of this specification, in which:

50 Figure 1, is a side elevation of the complete device. Fig. 2, shows a central vertical section corresponding to Fig. 1. Fig. 3, is in plan. In this figure the top or handle carrying member and the asbestos shield 55 are both removed to expose to view the heating elements in position. Fig. 4, corre-

sponds in most respects to Fig. 1 in this figure a switch has been added as shown to the left of the handle though secured thereto. Fig. 5, shows in detail another type of 60 heating unit which may serve equally well with my iron.

Similar letters of reference indicate like parts in all figures where they appear.

The body of the iron is indicated by A, it 65 is formed much like the ordinary sad iron having its interior hollowed out for the reception of the heating elements. Lugs A¹, which I may refer to as ears, are shown on one side of the upwardly extending or box 70 part of the iron, and a single hook A² is arranged upon the opposite side. These elements A¹, and A² will be again referred to and their functions described.

B indicates the top of the iron, in shape, 75 semi-domed or turtle-back, and formed integral with the top are a plurality of hooks of a size to operate conveniently with the ears or lugs A¹. A snap hook or catch on the opposite side of the top is indicated by 80 B². This hook, a spring catch, operates with the hook A² and provides the releasing means which allows the top to be removed from the iron.

B³ indicates the operating handle preferably of wood or other non-conducting material, it is supported by the posts B⁴ and B⁵. The lower end of the posts B⁴ and B⁵ are screw-threaded and after they have been passed through holes provided for them in 90 the top of the iron, the nuts B⁶, and B⁷ are tightened in place securing the handle upon the back. Formed integral with the post B⁵ or attached reliably thereto are the tubes b, b, and immediately below the tubes 95 holes are produced into the top of the iron that exactly register with the hole through the tube. These tubes and the holes beneath form the leading-in-means for the cable that is to supply electric current to the iron. 100

Now referring to Fig. 3, I will describe in detail the heating elements as they are shown there. The heating means is divided in this instance into three parts connected electrically in series, and although they differ somewhat in shape, the resistance of each part is equal to one third of the whole resistance. The section D, which is designed to fit closely into the point of the iron is in outline not unlike walls of the 110 irons interior. It is provided with a series of corrugations over its entire face. In the

trough between each pair of corrugations a wire or strip of resistance metal is placed, commencing at the point D¹ the wire is traversed back and forth continuously until 5 each trough is filled, the end is then secured to the connector block D². The section E is oblong, one of its faces is also provided with a series of corrugations into which a similar strip of resistance metal is 10 placed commencing with the connector block E³ and finishing with the connector block E². The section F is not unlike the section E, having the same corrugated face filled with resistance metal commencing with the 15 connector F² and terminating with the connector block F⁴. The number of sections used in any iron must be determined by the size and weight of the wire, but it is obvious that if a greater number of units be 20 used, the resistance of the wire or strip metal must be altered to suit the conditions.

It will also be obvious that the total amount of resistance in the sections must be determined by the voltage of the line 25 current with which the iron is to be used.

Between the top and the body of the iron I insert a metal plate R and above this an asbestos mat P both serving one with the other to deflect the heat downward and to 30 keep the top and operating handle of the iron cool, and between the asbestos mat and the back of the iron, I secure a bowed spring O arranged to hold the mat, the deflector plate, and the heating units reliably in 35 place.

It is sometimes desirable to have a controlling switch attached to the iron, and to that end I have designed the switch shown in Fig. 4. It will be observed that a slight 40 modification of the front handle supporting rod B⁴ is desirable when the switch is to be a part of the complete device.

H indicates a hinge, the outside block of which is secured to the rod B⁴, and H¹ a 45 tongue hingedly or pivotally connected to H and terminating at the inner end in the grip H². A rod H³ is acted upon by the tongue H¹; and a guide H⁴ serves to cause the rod to move with a perpendicular reciprocation when the position of the grip H² is changed. The switch proper, J is 50 of the double pole, double break variety having two blades and a cross bar connecting them, each blade hingedly connected to a lug. Two spring clips for each blade are provided as is shown at J¹. To the base of one of the spring clips of each pair, the leading in wires are secured and to the 55 other spring clips of the pairs, wires leading from the heating elements are secured.

The switch as I have shown it is nor-

mally open, that is the blades are out of the spring clips, and to accomplish this I provide the coiled spring K which is arranged between the pairs of spring clips 60 with one end resting upon a plate of non-conducting material and the other end resting on the cross-bar which connects the switch blades mechanically together.

Two pieces of slate or asbestos L and M 70 hold the spring clips J¹, and the hinge lugs for the blades J, and a cover N, which may also be of insulating material protects the whole from accidental contact with foreign material.

Modifications may be made within the scope of the appended claims without departing from the principle or sacrificing the advantages of this invention.

In Fig. 5 I have shown a somewhat different structure; in this device the heating units S are independently formed tubes having a metallic cap T secured upon each end. The resistance wire U is wound upon the tube S and has one of its ends secured to 80 each metallic cap, contact blocks V receive the metallic caps and the series of contact blocks normally insulated from each other are connected up in such a manner as to place the tubes in series electrically. 90

Other modifications may be made by a good mechanic.

Having carefully and fully described my invention, what I claim and desire to secure by Letters Patent is:—

1. In a sad iron the combination of a body, a plurality of heating units within said body, a cover hingedly connected to said body and having an operating handle and a switch arranged to serve with said 100 body, means arranged between said cover and said body for deflecting the heat downward upon said body and away from said cover and said handle and a spring carried by said cover for retaining said deflecting 105 means as specified.

2. In an electrically heated sad iron, a body, a cover, a handle therefor, a plurality of heating units in independent sections within said body, said units having their 110 conducting material arranged transverse to the length of said body and each said unit provided with temporary connecting means allowing one unit to be removed without disturbing the whole as herein specified. 115

Signed at New York city, in the county of New York and State of New York this 22nd day of October 1910.

EFFINGHAM LAURENCE POLLARD.
